COMBINATION SCREEN AND STORM
WINDOW

Stanley M. Bailey, Reading, and Stanley G. Kellogg, Weston, Mass.

Application October 10, 1947, Serial No. 779,042

1 Claim. (Cl. 160—182)

1

Our present invention relates generally to windows, and more particularly to an auxiliary window construction embodying an interchangeable storm and screen sash which may be installed or removed from within, and which may be interengaged with the building frame and assembled together in an air-tight association.

In prior combination windows of this general type, many difficulties have arisen due to the objectionable appearance caused by the outer projection and bulkiness of such windows, due to the awkwardly styled and positioned catches used, due to the flimsiness of the construction, and due to the complexity of their installation and the problems involving the interchanging of the storm and screen sashes.

The prime object of our invention, therefore, is to provide a combination screen and storm window unit which obviates the above and other objections and combines the qualities of strength, long life, easy installation, smooth operation, airtightness, and attractive appearance, as well as eliminating such burdens as heavy lifting, sticking, and dirt-trapping.

Another feature of our invention pertains to the novel and efficient channel strip construction with our novel locking, sealing, and holding flange, and reinforcing sliding edge element for housing the interchangeable storm and screen sashes and for adjustable attachment to the building window frame so that our combination window can be partly housed in such frame as to be unobtrusive and, in effect, constituting a weather-stripping construction, and an ornamental feature.

A further feature of our invention resides in the provision of unique means for locking the sashes tightly with the windowsill, after such sashes have been installed, yet permitting ready and easy removal when so desired.

A still further object of our invention is to provide means to hold the upper sash from sliding downwardly while the lower sash is being removed, thus facilitating removal and preventing injury to the operator.

Further advantages, features, and details of construction will be hereinafter more fully pointed out and claimed.

Referring to the drawings showing a preferred embodiment of our invention:

Fig. 1 is a front elevational view showing our combination window in installed position;

Fig. 2 is an enlarged cross-sectional view on the line 2—2 of Fig. 1;

Fig. 3 is an enlarged cross-sectional view on the line 3—3 of Fig. 1;

2

Fig. 4 is an enlarged cross-sectional view, similar to Fig. 3, showing a lower sash partly removed; and

Fig. 5 is an enlarged cross-sectional view on the line 5—5 of Fig. 1.

In the drawings, a building window frame of conventional design is shown, having like side sections 10—10, connecting top section 11, and a bottom sill 12. Adapted for association with each side 10 throughout the length thereof and with the top 11 between said sides is our novel channel strip, preferably stamped out of a sheet of aluminum or other suitable rust-proof material, and bent into desired shape as clearly shown in Fig. 5, comprising a bottom portion 14, a doubly reinforced outer side arm 15 extending at right angles to said portion 14, the outer fold of which portion 15 projects inwardly at approximately a forty-five degree angle to effect a flange 16, which, in turn, is formed with an attaching surface 17. For purposes of identification, we have designated each side-channel strip generally as 13, and the channel strip across the top as 18.

A doubly reinforced inner side arm 19 parallels the outer side arm 15 throughout the entire top channel 18 and throughout substantially the upper half of each side-channel 13; but along the lower half of each channel 13 to permit ready installation and removal of sashes adapted to slide therein, said inner arm 19 is clinched laterally against the bottom portion 14, as clearly shown in Fig. 2.

The channels 13 and 18 are secured to the side frames 10—10 and top 11 by any suitable means, such as a plurality of screws 20 driven thru the attaching surface 17. In this connection, it will be apparent that our novel channel strips 13 and 18 may be fastened to each frame 10 and top 11, as shown, with the bottom 14 flush therewith or removed slightly therefrom and with shims or the like therebetween, when adjustments are necessary to compensate for dimensional irregularities frequently encountered in building frame construction.

It will also be apparent from the novel design of the flange 16 and its attaching surface 17 that our channel strips 13 and 18 are enabled to be partially housed within the exterior limits of the frames 10—10, thus not only eliminating the bulky outside projections often prevalent in existing combination windows, but also, particularly in view of the detailed bevel arrangement of said flange 16, in effect adding an attractive appearance to the whole building.

It is believed that our unique channel construc-

tion is a distinct improvement in this art, and accordingly we wish to claim the same herein broadly.

Suitably secured in the bottom portion of the top channel 18 are one or more leaf springs 22-22 adapted to exert tension against the top frame 24 of an upper sash unit 23 when lifted into position, as shown in Fig. 3. We have shown the unit 23 as being of the standard type having said top frame 24, grooved bottom frame 25, and side frames 26-26 of proper dimensions to slide in the channels 13-13, such four frame members enclosing a usual glass pane 27.

A lower sash unit 28 is provided having side frames 29-29, grooved bottom frame 30 and top frame 31 formed with a tongue 32 to fit into said grooved frame 25 in weather-tight association, said frames, in turn, supporting as shown a glass pane 34 or, if desired, a ventilating screen. Positioned below said grooved frame 30 and cooperating therewith in weather-tight relation by means of the tongue 33 is a toggle apron 35, the lower surface of said apron 35 designed to rest upon the window sill 12 and form a tight joint therewith.

Loosely mounted on the sill 12 and secured thereto by loops 36-36 are a pair of combination brackets 37-37 which are positioned adjacent to and adapted to cooperate with said apron 35, functioning in the capacity of a spring clip or catch 38 when swung into the position shown in Fig. 3, and acting as an apron support 39 when swung into the position shown in Fig. 4.

To facilitate the installation and removal of the lower sash 28, we preferably attach by means of screws 41 a pair of finger-hooks 40-40 to the bottom frame 30, thus providing an operator with suitable lifting and pulling means for both purposes.

In order to hold the upper sash and window from dropping down entirely when the lower sash is swung outwardly and removed, we provide any suitable catch in position as indicated at 50, Fig. 1, to catch the upper sash when it is dropped slightly because of its weight and the expansive action of the springs 22 during the removal of the lower sash.

For this purpose, a spring-pressed plunger may be fitted, as shown at 50, to project in the path of the upper sash as the lower one is removed, or any other suitable catch can be manually compressed when it is desired to lower the upper sash completely and swing it inwardly for washing, removal, or replacing.

The important feature of our construction, utilizing the toggle apron 35 together with the advantages incident to our novel form of channel,

which is, in effect, a combined channel and weather-stripping element, will be readily appreciated. With the apron 35 swung inwardly and resting on the bevelled surface of the catch 39, the lower window or screen can be easily adjusted with the tongue 32 in the corresponding groove in the upper sash, and with the bottom portion fitting on the top surface of the tongue 33 in the apron 35. Thereupon, a slight pressure inwardly lifts both window frames against their own weight and the tension of the springs 22 by the toggle action provided by our construction, thereby firmly forcing both sashes and toggle apron in contact and alignment with the respective channels on each side, thereby holds all members under tension of the springs 22 in the topmost channel. Thus the operator is relieved of the exertion of lifting the sashes, both upper and lower, and forcing the same to slide in the channels since the simple toggle action afforded by the pushing in of the bottom sash does the lifting automatically.

We claim:

1. Interchangeable glass and screen construction of the kind described for association with a building window frame, comprising upper and lower sashes, U-shaped side channels in which the edge portion of said sashes may slide, the lower part of one flange of said U-shaped channel being omitted, said channels being constructed and arranged to be partly housed within the building window frame, and with an integral angularly extending bracing flange adapted to be attached outside said window frame, spring means in the top channel strip, a toggle apron positioned on the sill of said window frame and having interlocking means with the lower sash, swinging catches formed with a predetermined angle on which the toggle apron may rest in position to engage said interlocking means between the toggle and the lower sash, whereby swinging of the lower sash and toggle into vertical alignment will raise both sash and toggle into spring-tensioned engagement with the spring means in the top channel.
